UNITED STATES PATENT OFFICE

HENRY B. PATCH, OF KANSAS CITY, MISSOURI, ASSIGNOR TO GENESY ELECTRIC
LANTERN COMPANY, OF RAWLINS, WYOMING, A CORPORATION OF WYOMING

LANTERN

Application filed November 23, 1928. Serial No. 321,324.

My invention relates to improvements in lanterns. It relates particularly to novel means by which the operator of the lantern can shield his eyes from the glare of the lamp on the lantern, when the latter is swung or disposed in a certain position, as when it is being tilted in making inspections.

The object of my invention is to provide a novel glare shielding mechanism on the lantern which is simple, cheap, applicable to lanterns of a type now in use, and which can be operated by the hand which at the time is holding the handle of the lantern, which is strong, durable, not likely to get out of order, and which will retain the position to which it is moved without being moved by the swinging of the lantern therefrom.

The novel features of my invention are hereinafter fully described and claimed.

20 In the accompanying drawing which illustrates the preferred embodiment of my invention—

Fig. 1 is an elevation of an electric lantern provided with my improved glare shielding mechanism.

Fig. 2 is an enlarged fragmental sectional view on the line 2—2 of Fig. 1.

Fig. 3 is an enlarged section on the line 3—3 of Fig. 1.

30 Similar reference characters designate similar parts in the different views.

1 designates the body of a lantern of a type now in use, having a U-shaped handle 2, the arms of which are pivoted to the body 1 at 35 opposite sides thereof, and carrying at its lower end an electric lamp 3.

Two vertical parallel longitudinal guide bars 4 provide guiding means for a longitudinal stem 5 of a glare shielding member 40 having an arcuate body 6 adapted to be disposed in two positions, in one of which, as shown in solid lines in Figs. 1 and 2, it obstructs light projected in one direction laterally from the lamp 3, and in the other position, shown in dotted lines in Fig. 1, it will not obstruct the light from the lamp.

The stem 5 is provided at opposite edges with longitudinal flanges 7 respectively disposed at the inner sides of and slidably engaging the guide bars 4.

The stem 5 has at its upper end a lateral outwardly extending lip 8, which is adapted in either position of the shielding member to be engaged by the thumb of the hand which at the time is holding the handle 2. This 55 enables the operator with one hand to carry and swing the lantern and to at the same time operate the shielding member 6.

For reliably holding the shielding member in either of the positions to which it may be adjusted, so that in the swinging of the lantern, it will not accidentally become displaced from the set position, there is fastened to the side of the body 1 one end of a spring pawl 9, which at its free end has a projection 10 adapted to enter either of two holes 11 and 12, which are provided in the stem 5, one above the other, and in such locations, that, when the member 6 is in the shielding position, the projection 10 will enter the hole 11, 70 and, when the said member is retracted, the projection will enter the hole 12. The projection 10 is wedge shaped, so that pressure of sufficient force upwardly or downwardly on the lip 8, will cause the spring pawl projection 10 to release the stem. Upon the stem moving into the other position, the projection will automatically enter the other hole. 75

In the operation of the lantern, when it is desired to move the shielding member 6 to the upper and light unobstructing position, the operator uses the thumb of the hand which is holding the handle 2 to engage the lip 8 to draw upwardly the shield member. When the member arrives to a position in which the projection 10 of the pawl 9 enters the lower hole 12, said pawl releasably holds the shielding member 6 in its upper position. 85

When it is desired to return the shielding member to the obstructing lower position, the thumb is used to force the lip 8 downwardly until the projection 10 enters the hole 11, whereupon the pawl will retain the shielding member in the obstructing position. 90

I do not limit my invention to the structure shown and described, as modifications, within the scope of the appended claims, may be made without departing from the spirit of my invention.

What I claim is:—

1. In a lantern, the combination with a lantern body and a handle and lamp carried thereby at the bottom and outer side thereof, of a glare shielding member movable on the outer side of the side wall of said body to two positions, in one of which it will only obstruct light projected in one direction from said lamp and so disposed as to be engaged and moved to said positions by a hand which is holding the handle, and means for engaging and releasably holding said member in either of said positions.
2. In a lantern, the combination with a lantern body and a handle and a lamp carried thereby at the bottom and outer side thereof, of a guiding means on the outer side of the side wall of said body, a glare shielding member slideable on said guiding means to two positions in one of which it will only obstruct light projected in one direction from said lamp, and so disposed as to be engaged and moved to said two positions by a hand which is holding said handle, and having two holes, and a spring on said body adapted to enter either of said holes for releasably holding said member in either of said two positions.

In testimony whereof I have signed my name to this specification.

HENRY B. PATCHÉ.
